UNITED STATES PATENT OFFICE

2,564,628

MOTOR-DRIVEN HAIR CURLER OR WINDER

Everald J. Saucier, Hartford, Conn.

Application December 12, 1946, Serial No. 715,696

4 Claims. (Cl. 132—34)

1

This invention relates to the art of hair dressing, and an object of the present invention is to provide an efficient power-operated device for use in forming spiral curls or ringlets which lie flat against the scalp. The present application is a continuation-in-part of an application for patent filed by me on June 5, 1946, Serial Number 674,496, entitled "Hair Curler" and also of an application for patent filed by me on the 18th day of October, 1946, Serial Number 704,142, granted as Patent Number 2,443,544 and entitled "Hair Curler and Clip Assembly."

Among the objects of the present invention are to provide certain new and useful improvements over the hair curlers described and claimed in my aforementioned co-pending applications, and more specifically to provide a hair curler or winding device embodying an electric motor or similar prime mover which can be readily held in the hand and provides an efficient positive drive for the spool upon which the tress of hair is to be wound in the forming of the curl or ringlet.

The present invention, together with its objects and advantages will be best understood from the following detailed description when read in reference to the accompanying drawings in which are illustrated preferred embodiments of the invention and wherein;

Figure 1 is a side elevational view of a hair curler or winder embodying the features of the present invention, with the spool of the winder shown in longitudinal section;

Figure 2 is a fragmentary detail view of a clutch and transmission assembly forming part of the embodiment of the invention of Figure 1, and with the casing for said assembly shown in vertical section; and

Figure 3 is a view similar to Figure 1 and illustrating an alternate form of the invention.

Referring more in detail to the drawings, it will be seen that generally the hair curler or winder of the present invention comprises a spool 5 adapted to have a tress of hair wound thereon, an actuating shaft 6 for the spool and a small or miniature electric motor 7 for driving the shaft 6.

The spool 5 is somewhat similar to that shown and described in my hereinbefore identified co-pending applications, and is characterized by a frusto-conical end portion 8 constituting a barrel section upon which the strand of hair to be curled is wound. Also, and as characterizes the spool illustrated in my previously referred to co-pending applications, the spool herein illustrated is provided with a clip indicated generally by the

reference numeral 9 and cooperative with the barrel portion 8 of the spool for securing the tip end of the strand or tress of hair to the barrel portion 7 preparatory to winding the strand or tress onto the spool.

The clip 9 embodies a jaw portion 10 that overlies the frusto-conical portion 8 of the spool and is adapted to be flexed into and out of clamping position with respect thereto. This jaw 10 is formed integral with a hand lever 11 that extends in divergent relationship to a lever 12 that is formed integral with, and is joined to the jaw 10 and hand lever 11 at the junctions of said jaw and lever through the medium of a web 13. As shown, the clip is disposed on the spool with the levers 11 and 12 located at one side of the spool flange 14 and the jaw 10 located at the opposite side of said flange; the flange 14 being provided with a slot or opening therein to permit such assembly, and as is more fully disclosed in my co-pending application, Serial Number 674,496.

The spool 5 is fixed to its actuating shaft 6 in any suitable manner, as by being keyed thereto, as indicated at 15, to rotate with said shaft.

In accordance with the present invention, the shaft 6 is driven from an electric motor 7 for effecting a positive rotation of the spool incidental to the winding of the hair on the latter.

In the form of the invention shown in Figure 1, the electric motor 7 is illustrated as being in the form of a small or miniature motor which may be readily held in the palm of the hand of the operator. The shaft of this motor is indicated by the reference numeral 16 and for transmitting drive from the shaft 16 to the shaft 6, there is provided an encased clutch and transmission assembly indicated generally by the reference numeral 17.

As shown in Figure 2, the aforementioned assembly 17 includes a suitable casing or housing 18 that has opposite end walls thereof provided with bearings 19 and 20. The free end of the motor shaft 16 is journaled in the bearing 19 and extends into the housing 18 in alignment with the free end of the actuator shaft 6, and which end of the actuator shaft is journaled in the bearing 20 and extends into the housing 18. On the inner end of the shaft 6 are beveled gears 17' and 18' spaced apart as shown.

For transmitting drive from the motor shaft 16 to the shaft 6 for rotating the latter in one direction there is provided on the inner end of the shaft 16 a clutch disc 20' with which is co-operable a clutch disc 21 provided on the inner end of a stub shaft 22 journaled in a bearing 23

provided on one wall of the housing 18. On the inner end of stub shaft 22 is a gear 24 adapted to be moved into and out of mesh with the gear 17'. It will thus be seen that when disc 21 is moved into frictional contact with the periphery of disc 20', gear 24 will move into engagement with gear 17' and therefore drive will be transmitted from shaft 16 through the discs 20', 21 to stub shaft 22, and from stub shaft 22 through the gears 24 and 17' to the shaft 6 for rotating the spool 5 in one direction. 10

Arranged in alignment with the stub shaft 22 is a similar stub shaft 25 that is journaled in a bearing 26 provided in the wall of the housing 18. On the inner end of this stub shaft is a disc 27 that is adapted to be moved into and out of engagement with clutch disc 20'. Also on the inner end of stub shaft 25 is a gear 28 that is adapted to be moved into and out of mesh with the gear 18'. Thus it will be seen that when discs 27 and 20' are in frictional contact, gears 28 and 18' are in mesh and drive is then transmitted from the shaft 16 to the shaft 6 for rotating the spool 5 in a reverse direction. 15

Discs 21 and 27 are yieldably retained out of engagement with disc 20', and gears 24 and 28 are yieldably retained out of mesh with gears 17' and 18' through the medium of coil springs 29 housed within the bearings 23, 26 and impinging against buttons 30, 31 provided on the outer ends of the respective shafts 22 and 25. 20

In the form of the invention shown in Figure 3, an assembly corresponding to the hereinbefore described assembly 17 is eliminated. In lieu thereof the electric motor, indicated in said figure by the reference numeral 7a, and employed for driving the spool 5 is of a well known commercial type, being a reversing type 110 volt with a reversing type switch 32. Consequently, by proper manipulation of the switch 32, the spool 5 may be rotated in either of two directions. Also, and as is apparent in this alternate form of the invention, the motor shaft and the actuator shaft are substantially one and the same, the actuating shaft being but an integral extension of the motor shaft as so illustrated. 25

In using the hair curler or winder embodying the features of the present invention, the same may be readily held in the hand of the operator with the motor (7 or 7a as the case may be) fitting conveniently in the palm of the hand. With the other hand, the tip end of a strand of hair drawn outwardly from the head of the patron is placed upon the end 8 of the spool 5 and clamped thereon in an obvious manner by the action of the clamping jaw 10. After the tip end of the strand has been secured in position on the spool 5, the starter switch of the motor 7 is thrown for rotating the spool 5 through the driving action of the shaft of the motor. 30

When the device embodying the assembly of Fig. 1 is employed, the operator will apply pressure with the fingers either to the button 30 or to the button 31 for controlling the direction of rotation of the spool 5 as the desire of the operator or the form of hair dressing may dictate. 35

When the form of the device embodying the assembly of Figure 3 is employed, the direction of rotation of spool 5 is conveniently controlled through the medium of the switch 32 with which the motor 7a is equipped as is believed to be apparent. 40

After the strand of hair has been wound on the spool 5, the coil is compressed and removed from the spool in any manner found desirable 45

or in the manner and through the use of devices particularly provided for that purpose and as disclosed in my aforementioned co-pending applications. 5

While I have herein described the preferred forms of my invention, it will be understood that the same may be varied without departing from the spirit of the invention or the scope of the claims hereto appended. 10

What I claim is:

1. For use in winding hair on a spool, a clutch and reversible transmission assembly for operative connection with the spool comprising an actuating shaft for the spool, a motor-driven disk, clutch disks disposed to frictionally engage opposite peripheral sides of the motor-driven disk, a gear mounted upon the central portion of each clutch disk and rotating in response thereto, gears on the spool-actuating shaft supplemental to the gears on the clutch disks, and a push button related with each of the clutch disks for urging the corresponding clutch disk against the motor-driven disk and the corresponding gear against its complementary gear on the actuating shaft for the spool, whereby the spool may be rotated in either direction. 15

2. In a hair winding device of the type embodying a spool for winding thereon a coil of hair and a motor for driving the spool, a clutch and reversible transmission assembly interposed between the motor and the spool including a spool actuating shaft, a disk in driven engagement with the motor, clutch disks disposed to frictionally engage opposite peripheral sides of the motor-driven disk, inter-engaging means on the spool actuating shaft and on each of the clutch disks coacting upon frictional engagement of a selected clutch disk with the motor-driven disk to transmit drive to the spool actuating shaft for rotating the latter in a predetermined direction, and a push button related with each of the clutch disks for urging the corresponding clutch disk against the motor-driven disk. 20

3. In a motor-driven hair winding device of the type embodying a spool for receiving a coil of hair, an actuating shaft for the spool, and a motor for driving said actuating shaft; a clutch and reversible transmission assembly interposed between the motor and said actuating shaft including a disk in driven engagement with the motor, clutch disks disposed to frictionally engage opposite peripheral sides of the motor-driven disk and selectively movable into and out of engagement with said motor-driven disk, a gear on said actuating shaft and a gear on one of the clutch disks inter-engageable upon frictional engagement of said one clutch disk with the motor-driven disk for transmitting drive in one direction to the actuating shaft, and a second gear on the actuating shaft and a gear on the other of the clutch disks inter-engaging when said other clutch disk is in frictional engagement with the motor-driven disk for transmitting drive to the actuating shaft for rotating the latter in a reverse direction. 25

4. In a hair winding device of the type embodying a spool for receiving the coil of hair to be wound and a motor for driving the spool, a manually operable clutch and transmission assembly interposed between the motor and spool of the device for controlling the transmission of drive to the spool and the direction of rotation of the spool including a motor-driven disk, clutch disks selectively movable into and out of frictional driven engagement with the motor-driven 30

disk, and transmission gearing connected with the spool and the clutch disks operable in response to frictional engagement between the motor-driven disk and a selected clutch disk for effecting a driving connection, through the frictionally engaged disks and said gearing, between the motor and the spool for revolving the latter in a predetermined direction.
